United States Patent Office

Des. 203,156
Patented Dec. 14, 1965

203,156

HINGE

Raymond Tintary, Covina, and Anthony Joseph Carsello,
Hollywood, Calif., assignors to Ajax Hardware Manufacturing Corp., City of Industry, Calif., a corporation of California

Filed Mar. 3, 1965, Ser. No. 84,061

Term of patent 14 years

(Cl. D10—9)

FIG. 1.

FIG. 2.

FIG. 3.

FIG. 5.

FIG. 1 is an isometric view of the hinge of our design;
FIG. 2 is a side elevational view;
FIG. 3 is a front elevational view;
FIG. 4 is a rear elevational view; and
FIG. 5 is a top plan view.

The dominant features of the design reside in the portions shown in full lines.

We claim:

The ornamental design for a hinge, as shown and described.
